ASSIGNORS TO THE YALE & TOWNE MANUFACTURING COMPANY, OF STAMFORD,
CONNECTICUT

CYLINDER LOCK

Application filed May 27, 1927. Serial No. 194,722.

This invention relates to improvements in cylinder lock structures and more particularly to means for insuring the proper normal use and operation of the key.

5 In pin tumbler locks, improper operation of a key is sometimes possible due to the fact that the key is not fully inserted, the pins then being allowed to ride on the slopes instead of in the depressions of the key.

10 Objects of the present invention are to prevent error in the insertion of a key into a pin tumbler lock; to render normal complete insertion of the key necessary to the operation of the lock, and to provide simple 15 and efficient means which shall be operable to insure full insertion of the key into the lock before the plug can be turned to effect operation of the lock.

With these and other objects in view, the 20 invention consists in certain novel features as hereinafter set forth and pointed out in the claims.

In the accompanying drawings:—

25 Figure 1 is a view illustrating our improvements;

Figure 2 is an enlarged transverse sectional view;

30 Figure 3 is an enlarged transverse sectional view showing the lock cylinder and the plug cavity therein;

Figure 4 is a transverse sectional view of the plug;

Figure 5 is a detail view of the U-shaped member, and

35 Figure 6 is a detail view of the key.

In the drawings, a lock cylinder is represented at 1, and is made with a cavity or bore 2 for the accommodation of the plug member 3 of the lock, but the pin tumbler mechanism has been omitted as a detail showing of the same in the drawing is not deemed essential to an understanding of the present invention.

40 The plug 3 is provided with the usual key slot 4 and near one end the plug is made with transversely disposed sockets or bores 5, 5 disposed at respective sides of the key slot 4 for the reception of the parallel arms of a U-shaped member 6 which spans the key 7 when the latter is in the plug 3. The

wall of the plug bore in the cylinder is made with a depression 8 into which the U-shaped member 6 enters when the plug is in locked position, and thus passage of the key into the plug is permitted. If the 55 key be provided with a notch or recess 9 correctly located, the cross bar of the U-shaped member 6 will ride into such notch upon the turning of the key plug. If the notch is incorrectly placed or the key is not fully inserted, the U-member will of course prevent 60 operation of the lock by wedging in between the key and the cylinder.

Heretofore, it has been the custom to form the forward end of the key 7 relatively blunt, 65 but with a key thus formed, it has been found that it may be improperly operated at times by incompletely inserting the key so that the pin tumblers will ride on the slopes of the key rather than in the depressions. In accordance with the present invention, the forward end of the key is cut away sharply from its No. 1 bitting as indicated at 11 Figure 1, so that if the proper key is not fully inserted or a key of a slightly different contour is but 70 partially inserted, a considerable drop of the No. 1 pin will be obtained and the lock secured against operation. The proper key must, therefore, be employed and it must be fully inserted to insure its proper operation in effecting the turning of the plug member of the lock. It is possible to have a sharp drop from a bitting other than bitting No. 1, and under certain circumstances it might be advisable to have a sharp rise from a bitting instead of a drop. Any definite change in key 75 contour whereby a considerable pin movement is obtained by only a slight key movement, is within the scope of this invention.

80 By provision of the improvements embodying the movable U-shaped member and its cooperation with the plug, cylinder and key, complete insertion of the key will be insured.

85 It will be observed that the key construction hereinbefore described will serve to prevent slight error in key insertion and the use of the U-member as previously described will prevent greater error.

90 Having fully described our invention what 100

we claim as new and desire to secure by Letters-Patent, is:—

1. In a pin-tumbler lock mechanism, a plug having a key slot and transverse bores at respective sides of the key slot, a U-shaped member having its parallel arms freely entering said transverse bores, a cylinder having a recess to receive said U-shaped member and permit insertion of a key into the key slot in the plug, the key having a recess to receive the cross bar of said U-shaped member.
2. In a pin tumbler lock, a U wedging member mounted in alined recesses of the plug and cylinder when the lock is in locked position, said U member being adapted to be cammed entirely into the plug recess upon slight movement of the plug in order to permit full movement thereof, the key of said lock being slotted to permit this necessary movement.
3. In a pin tumbler lock having alined recesses in the plug and cylinder, a U member having its vertical arms normally in the plug recess and its horizontal member in the cylinder recess, said lock being operable by a slotted key, said horizontal member being adapted to cam upwardly into said key slot and plug recess upon operation of the lock.
4. In a pin tumbler lock including a plug and cylinder, a U-shaped member mounted to operate in alined recesses of the plug and cylinder, said U-member being adapted to be cammed entirely into the plug recess upon operation of the lock, the key for the lock being slotted to permit such camming movement so as to render possible lock operation.

In testimony whereof, we have signed this specification.

FRANK E. THOMPSON.
ALFRED LAWRENCE.
